US00D802593S

(12) **United States Design Patent** (10) Patent No.: **US D802,593 S**
Zhang et al. (45) Date of Patent: ** Nov. 14, 2017

(54) **SCANNER**

(71) Applicant: **Hand Held Products, Inc.**, Fort Mill, SC (US)

(72) Inventors: **Pengfei Zhang**, Shanghai (CN); **Dezhi Yang**, Shanghai (CN)

(73) Assignee: **Hand Held Products, Inc.**, Fort Mill, SC (US)

(**) Term: **15 Years**

(21) Appl. No.: **29/555,990**

(22) Filed: **Feb. 26, 2016**

(30) **Foreign Application Priority Data**

Aug. 28, 2015 (CN) 2015 3 0329152

(51) **LOC (10) Cl.** **14-02**

(52) **U.S. Cl.**

USPC **D14/420**

(58) **Field of Classification Search**

CLAIM

The ornamental design for a scanner, as shown and described.

DESCRIPTION

FIG. 1 is a top plan view of a scanner in accordance with the present design;

FIG. 2 is a bottom view thereof;

FIG. 3 is a left side elevation view thereof;

FIG. 4 is a right side elevation view thereof;

FIG. 5 is a rear elevation view thereof;

FIG. 6 is a front elevation view thereof; and,

FIG. 7 is a front perspective view thereof.
